WAFFLE IRON

Louis Vitantonio, Cleveland, Ohio

Application March 31, 1955, Serial No. 35,311

Term of patent 3½ years

(Cl. D81—10)

Figure 1 is a perspective view of a waffle iron in open position, embodying my new design.

Figure 2 is a side elevational view of the waffle iron with the parts in closed position.

Figure 3 is an end elevational view of the iron in closed position.

Figure 4 is a plan view of one of the sections of the waffle iron.

Figure 5 is a plan view of the other section of the waffle iron.

Figure 6 is a plan view showing the waffle iron in closed position.

I claim:

The ornamental design for a waffle iron, as shown.
